UNITED STATES PATENT OFFICE

ROBERT J. BOGUE, OF GOODNIGHT, TEXAS

PISTON FOR ROTARY STEAM MOTORS

Application filed June 3, 1926. Serial No. 113,576.

This invention supplies a piston for a rotary steam motor of novel and peculiar construction embodying packing which is forced outwardly by steam pressure to maintain a close joint with the chambers to prevent loss of pressure.

While the drawings illustrate a preferred embodiment of the invention, it is to be understood that in adapting the means to meet specific needs and requirements, the design may be varied and changes in the minor details of construction may be resorted to within the scope of the invention as claimed, without departing from the spirit thereof.

For a full understanding of the invention and the merits thereof, reference is to be had to the following description and the drawings hereto attached, in which,—

Figure 1 is a side view of a rotary engine embodying the invention,

Figure 2 is a vertical transverse sectional view on the line 2—2 of Figure 1,

Figure 3 is an enlarged view of one of the pistons, the near plate being omitted,

Figure 4 is a longitudinal edge view of a piston,

Figure 5 is a detail sectional view on the line 5—5 of Figure 4, and

Figure 6 is a detail perspective view of the expandible packing of one of the pistons and the strips coacting therewith to maintain a tight joint between the overlapping ends of adjacent elements.

Corresponding and like parts are referred to in the following description and designated in the several views of the drawings by like reference characters.

The stator comprises similar sides 1 and 2 which are bolted or otherwise secured together to form a stator or casing for reception of the rotor 18 which obtains a snug fit therein, there being packing 3 between the meeting faces to preserve a steam tight joint. The rotor 18 is keyed or otherwise made fast to a shaft 4 which is mounted centrally of the side members, the projecting ends of the shaft 4 receiving pulleys or fly wheels 5. Each of the side members comprising the stator is provided with concentric chambers 6 in which the ends of the pistons carried by

the rotor operate. The chambers are of circular outline and each extends approximately three-fourths of a circle, said chambers tapering at opposite ends. The chambers formed in the side member 1 are designated by the numerals 6 and 7, the inner chamber 6 being of considerably less cross sectional area than the outer chamber 7. The chamber 6 is of uniform width throughout its circumferential length but gradually decreases in depth at its opposite ends, which merge into the inner face of the member substantially as indicated by the dotted lines in Figure 2.

The steam or like expansive motive medium is supplied to one end of the chamber 6 by means of a pipe 8 connected with a suitable source of supply, and the opposite end of the chamber 6 communicates with one end of the chamber 7 so that the spent steam from the chamber 6 enters the chamber 7 and operates therein by expansion. The outlet at the opposite end of the chamber 7 opens into the atmosphere for discharge of the steam after it has operated expansively.

The side member 2 is provided with an inner circumferential chamber 12 corresponding to the circumferential chamber 6 of the side member 1. The chamber 12 has a reverse arrangement to the chamber 6, that is, the space formed between the ends thereof is located directly opposite the middle portion of the chamber 6. This brings the space between the ends of the chamber 6 directly opposite the middle portion of the chamber 12. The side member 2 is also provided with a circumferential chamber 13 corresponding to the chamber 7 and having a reverse arrangement, that is, with the space between its ends arranged diametrically opposite the space midway between the ends of the chamber 7. Opposite ends of the several chambers are reversely inclined and the intermediate portion is of a uniform depth. A pipe 14 leading from a suitable source of steam supply communicates with the inlet at one end of the chamber 12. The outlet at the opposite end of the chamber 12 communicates with one end of the chamber 13 and provides for discharge of the steam from

the chamber 12 into the chamber 13 to operate therein by expansive action. The outlet at the opposite end of the chamber 13 provides for discharge of the steam therefrom into the open air.

The rotor 18 is provided at diametrically opposite points with a pair of transverse openings in line with the respective inner and outer concentric chambers. Pistons 21 are mounted in the openings alined with the chambers 6 and 12 to slide transversely of the rotor and alternately operate in said chambers. Other pistons 22 are similarly mounted in the openings alined with the chambers 7 and 13. The pistons 21 and 22 are of like construction, the only difference residing in the width, the pistons 22 being wider than the pistons 21 to correspond with the width of the outer chambers 7 and 13. At one position of the rotor 18, as shown most clearly in Figure 2 of the drawings, the end portion of one of the pistons 21 projects into the chamber 12 and the opposite end of the piston is in engagement with the side of the 25 stator in the space between the ends of the chamber 6. The other piston 21 at the same time has its opposite end portion projected into the chamber 6 and its other end in the space formed between the ends of the chamber 12. The outer pistons 22 are reversely disposed, the end of one piston projecting into the chamber 7 and the opposite end of the other piston projecting into the chamber 13. Roller bearings are provided upon the 30 sides of the rotor at sides of the respective pistons 21 and 22 so as to minimize the resistance to their transverse sliding movements.

The pistons are of like formation, the construction being shown in detail in Figures 3 to 6, both inclusive. Each of the pistons comprises a middle plate 25 and side plates 26, the several plates being of like width and length. The side plates 26 are of uniform 45 thickness throughout whereas the middle plate 25 has its central portion 27 of greater thickness than its marginal portions and projecting upon opposite sides to a like extent, whereby to provide marginal spaces between the several plates for the reception of packing to maintain a steam tight joint between the pistons and the walls of the chambers and the openings in which the pistons are mounted. The raised portion 27 at each side 50 of the middle plate 25 is formed at each end with a transverse channel 28 and a longitudinal channel 29 in communication at its inner end with the transverse channel 28. Openings 30 are formed in end portions of the side plates 26 and communicate with the transverse channel 28 to supply steam thereto, which is utilized to force the packing outwardly to main a steam tight joint. The packing at each side of the middle plate 25 55 consists of four angle elements 31 having

their end portions halved and overlapped, as shown most clearly in Figures 4 and 6. The packing fits snugly between the middle and side plates and is of a width to leave a space 32 between the outer edges of the raised portions 27 and the inner edges of the packing and this space receives strips 33 which serve to close the spaces between the overlapping ends of adjacent packing elements to prevent loss of pressure. When the steam pressure 70 is applied the steam enters the lateral openings 30 of the side plates 26 and enters the channels 28 and 29 and passes into the spaces 32, thereby forcing the strips 33 and the packing elements outwardly, with the result that loss of pressure is prevented and a steam tight joint between the pistons and the walls of the chambers and the openings of the rotor is maintained.

In the operation of the engine live steam 85 at boiler pressure is admitted to each of the inner chambers 6 and 12 by means of the pipes 8 and 14. This steam operates upon the end portions of the pistons 21 projecting into the respective chambers 6 and 12, thereby imparting a rotary movement to the rotor 18. When the rotor reaches a point in its travel to uncover the respective outlet ports the live steam passes from the respective chambers 6 and 12 into the outer expansion chambers 7 and 13 and operates expansively on the respective pistons 22, the end portions of which project into the respective expansion chambers. The motor now continues to operate both by direct pressure of the steam and by 90 expansive action thereof and the respective pistons 21 and 22 are alternately shifted from one chamber to the other, as will be readily appreciated. The steam after acting expansively escapes into the atmosphere. The inner sides of the several chambers are closed by the rotor and the packing 3 is disposed to maintain a steam tight joint at the outer walls of the chambers. As shown most clearly in Figure 2 of the drawings, opposite ends of 105 corresponding pistons project beyond opposite sides of the rotor, hence the driving force of the steam is expended uniformly upon opposite sides of the rotor, thereby preventing any binding or torsional action. The bottom walls of the respective chambers incline at opposite ends thereof to insure a shifting of the pistons, as they reach the ends of the 110 respective chambers and the construction is such as to provide chambers of practically uniform depth, the end portions of corresponding chambers being opposite one another and reversely inclined, as shown most clearly in Figure 6. The inner chambers 6 and 12 are of less capacity than the outer chambers 7 and 13 and this is of advantage in the conservation of power and the utilization thereof to the best possible advantage because the expanding steam acts upon a greater 115 120 125 130

ton area than the live steam at boiler pressure.

Having thus described the invention, I claim:

1. A piston comprising a rectangular plate having a raised central portion formed in its outer side with intersecting transverse and longitudinal channels, a companion plate co-extensive with the first mentioned plate and placed against the raised portion thereof, and having openings in communication with the said channels, packing in the space formed between the marginal portions of the two plates exterior to the said raised portion and having the meeting ends halved and overlapped, and strips in the marginal space in the rear of the packing to close the joints between the meeting ends thereof.

2. A piston comprising rectangular and co-extensive middle and side plates, the middle plate having a centrally disposed raised portion at each side forming spaces between the marginal portions of the plates, the raised portions of the middle plate having intersecting transverse and longitudinal channels in their outer sides, and the side plates having openings in connection with the intersecting channels, angle packing in the marginal spaces having the meeting ends halved and overlapped, and strips in the spaces in the rear of the packing and closing the joints between the meeting ends thereof.

In testimony whereof I affix my signature.
